UNITED STATES PATENT OFFICE.

BREWSTER W. CRIBB, OF OMAHA, NEBRASKA.

METALLIC PACKING.

SPECIFICATION forming part of Letters Patent No. 772,788, dated October 18, 1904.

Application filed February 5, 1904. Serial No. 192,184. (No model.)

To all whom it may concern:

Be it known that I, BREWSTER W. CRIBB, a citizen of the United States, residing at Omaha, in the county of Douglas and State of Nebraska, have invented certain new and useful Improvements in Metallic Packing; and I do hereby declare the following to be a full, clear, and exact-description of the invention, such as will enable others skilled in the art to which it applies to make and use the same.

My invention relates to metallic packings for reciprocating rods, and especially to that class wherein the packing is held in intimate contact with the rod by the force of the expansive fluid therearound.

The object of the invention is to provide a simple, cheap, durable, and effective metallic packing, and comprises a plurality of separable sections so constructed and arranged relatively to each other as to be readily taken off or applied to the rod without disconnecting the rod itself.

To more fully disclose my invention, I will describe the same as applied to the cylinder of the ordinary type of steam-engine, and referring now to the drawings illustrating the same, in which like letters designate the same parts in the several views, Figure 1 is a central section through the stuffing-box and gland-plate, the piston and packing being shown in elevation; Fig. 2, a side elevation of one of the sectional packing-rings with the retaining-band therearound; Fig. 3, a side elevation of the follower or joint ring; Fig. 4, a plan view of the retaining-band for the sectional packing-ring; Fig. 5, a diagrammatic view illustrating the preferred normal shape of the retaining-band, the dotted lines indicating the position it assumes when secured around the packing-rings; Fig. 6, a side elevation of the abutment-ring; Fig. 7, a side elevation of another form of the follower or joint ring; and Fig. 8, a central section, similar to Fig. 1, with the form of joint-ring illustrated in Fig. 7 applied thereto.

A designates the stuffing-box on the cylinder-head, and B the piston-rod.

C is a plate used in lieu of the usual gland and which I term the "gland-plate." The inner face of this gland-plate is provided with a cir-

cumferential groove to receive therein a copper gasket D, adapted to be flattened against the outer face of the stuffing-box for forming a steam-tight joint between the gland-plate and stuffing-box. As illustrated, the gland-plate C will be detachably but securely fastened to the stuffing-box by suitable bolts or screws e.

The packing proper consists of one or a plurality of rings E, formed of suitable metal, preferably hard Babbitt metal. These rings comprise a plurality of segmental members E', preferably of semicircular conformation, the ends of which are beveled to form a sliding joint when the rings are assembled. This beveled surface may be of any suitable disposition; but I prefer to cut away the ends of the rings, as illustrated in Fig. 2, so that each sectional member of the ring is provided at one end with a concave bearing-surface e and at its opposite end with a convex bearing-surface e', the said bearing-surfaces extending in an unobstructed manner transversely of the members, and the ends of the members are provided with the convex bearing-surface, being also cut away to form the rounded surface e'', so that the end will not project over the peripheral surface of the packing-ring as the inner surface of the same is worn away by the reciprocating rod. These packing-rings are held from longitudinal displacement by the abutment-ring F and the joint-ring G.

The construction of the abutment-ring F is clearly shown in Fig. 6 and comprises the sectional members F', the abutting ends of which are provided with flat faces F'', which prevent the members from closing in and bearing on the rod, as do the sections of the packing-ring.

The ring F is slightly greater in diameter than the packing-rings E, so as to form a projecting shoulder for maintaining the position of a retaining-band (hereinafter described) on the packing-rings. The sectional members F' of the abutment-ring F are held in position in any suitable way, preferably, as shown, by a copper wire f, extending in a groove around the periphery thereof.

The joint-ring G comprises the sectional members G' G'', the ends of one of said mem-

bers, G' , being slotted, as at g^0 , to receive the tenon member g , formed on the other said section, and are held in their assembled position by the soft metallic rivets g' .

5 The bore of the joint-ring G is slightly larger than the reciprocating rod, as indicated by dotted lines in Fig. 1, and the outside diameter of said ring is slightly less than the bore of the stuffing-box, this construction being preferable to allow for any vibration of the reciprocating rod.

10 H represents retaining-bands adapted to extend around the periphery of the packing-ring and hold the same assembled when there is no steam in the chamber, it being understood that the intimate contact of the packing-rings with the reciprocating rod is caused by the pressure of the expansive fluid thereupon. These retaining-bands H comprise a 15 strip of resilient metal provided with the aperture H^0 at one end and a hooked tongue portion H' at the other. These bands may also be provided on their under face with the teeth or projections h , adapted to be embedded in each section of the packing-ring—for 20 instance, by a slight tap of a hammer. These projections engaging the sectional members of the packing-ring will serve to make a more perfect unison of movement between the sections, as it will be obvious that being thus connected together the movement of one member toward the reciprocating rod will impart a corresponding movement to the other member through the medium of the retaining-band, thus compensating for any unevenness of fluid-pressure on the sectional 25 members.

In order that more resiliency be given to the retaining-band H , it is preferred that it 30 be normally formed as indicated in Fig. 5, the dotted lines indicating the position when it is fastened around the rings.

35 In Figs. 7 and 8 I have illustrated a slightly-modified form of the joint-ring. In this construction the mortise-and-tenon joint is dispensed with and the ends of the sectional members G^3 and G^4 have flat faces, the two members being securely fastened together by the screws g^2 . The peripheral surface of the 40 member G^3 is recessed, as at G^0 , forming seats for the heads of the screws g^2 , the end faces of the member G^3 being provided with apertures opening into the recesses G^0 . These apertures in the member G^3 are adapted to 45 register with screw-threaded recesses formed in the member G^4 , in which the screws g^2 operate. The screws g^2 are provided with transverse apertures adapted to register with apertures extending transversely of the member 50 G^4 and through which are driven pins g^3 for locking the parts securely together and preventing the screws from turning and the parts becoming loosened.

The conjoint thickness of the various rings

is such that when assembled in the stuffing-box chamber there is a small space (indicated by the letter X) for admitting the expansive fluid within the stuffing-box chamber and at the same time preventing the binding of the joint and abutment rings against the walls of the stuffing-box should there be vibration of the reciprocating rod.

55 It will thus be seen that my metallic packing-rings and the associated parts for holding the same in position comprise sectional members, so that the packing may be readily put on any reciprocating rod at any time to replace any breakage that may occur to the packing, an important feature, especially in railroading.

80 I do not wish to limit myself to the exact details as shown, as modifications might be made without departing from the spirit of my invention; but

What I claim is—

85 1. A metallic packing-ring, comprising a plurality of segmental members, the opposite ends of each of said members being of a concave and convex conformation, respectively, for forming an unobstructed bearing-surface 90 transversely of the members, and the concave face of one of said members adapted to form a sliding joint with the convex face of the opposite member.

95 2. A metallic packing-ring, comprising a pair of semicircular members, the opposite ends of each of said members being of a concave and convex conformation, respectively, for forming an unobstructed bearing-surface 100 transversely of the members, and the concave face of one of said members adapted to form a sliding joint with the convex face of the opposite member.

105 3. A metallic packing-ring, comprising a plurality of segmental members, the opposite ends of each of said members being of a concave and convex conformation, respectively, for forming an unobstructed bearing-surface 110 transversely of the members, and the concave face of one of said members adapted to form a sliding joint with the convex face of the opposite member, and a resilient band encircling said members for holding them in their assembled position.

115 4. A metallic packing-ring comprising a plurality of segmental members, the ends of said members being suitably beveled off to form a sliding joint therebetween, a resilient band, encircling said members for holding them in their assembled position, having a bent portion to increase its resiliency when encircling said members, and means for securing the ends of same.

120 5. A metallic packing-ring comprising a plurality of segmental members, the ends of said members being suitably beveled off to form a sliding joint therebetween, a resilient band encircling said members for holding

them in their assembled position, and means for securing said band to said segmental members for imparting a corresponding movement to all of said segmental members upon 5 the movement of any one.

6. In a packing-ring for reciprocating rods, the combination with a packing-ring comprising a plurality of segmental members, the opposite ends of each of said members being provided respectively with a concave and convex 10 bearing-surface, the concave face of one of said members being adapted to form a sliding joint with the convex face of the opposite member, of a sectional ring disposed adjacent 15 said packing-ring for preventing its displacement longitudinally of said rod, means for retaining the sectional members of said adjacent ring when assembled, and means for retaining the segmental members of said packing-ring when assembled, comprising a resilient band extending peripherally there-around.

7. In a packing for reciprocating rods, the combination with the stuffing-box surrounding said rod, of metallic packing-rings within the bore of said stuffing-box, comprising a plurality of segmental members, the ends of said members being suitably beveled off to form a sliding joint therebetween, means for 20 holding said members together, a sectional abutment-ring located on one side of said packing-rings and means for holding the sections of said abutment-ring together, a sectional joint-ring located adjacent the other 25 side of said packing-rings and means for holding the sections of said joint-ring together, a gland-plate engaging the outer face of said stuffing-box, and means for securing said gland-plate to said stuffing-box.

8. In a packing for reciprocating rods, the combination with the stuffing-box surrounding said rod, of metallic packing-rings within the bore of said stuffing-box, comprising a pair of substantially semicircular members, 30 the ends of said members being suitably beveled off to form a sliding joint therebetween, means for holding the sectional members of said packing-rings together, a sectional abutment-ring located on one side of said pack-

ing-rings, and means for holding the sections 50 of said abutment-rings together, a sectional joint-ring located adjacent the other side of said packing-ring, and means for holding the sections of said joint-ring together, a gland-plate provided with an annular groove, a 55 gasket located within said groove and engaging the outer face of the stuffing-box, and means for securing said gland-plate to said stuffing-box.

9. The combination with the stuffing-box 60 and reciprocating rod therethrough, of a metallic packing for said rod, comprising the sectional metallic packing-rings of lesser diameter than the bore of the stuffing-box, means normally holding the sections of each of said 65 packing-rings together, an abutment-ring adjacent said packing-rings, a joint-ring located on the other side of said packing-rings comprising a pair of substantially semicircular members, clamping means engaging the ends 70 of said members, a gland-plate engaging said joint-ring, and means for securing said gland-plate to said stuffing-box.

10. The combination with the stuffing-box and reciprocating rod therethrough, of a metallic packing for said rod, comprising the sectional metallic packing-rings of lesser diameter than the bore of the stuffing-box, means normally holding the sections of each of said 75 packing-rings together, an abutment-ring adjacent said packing-rings, a joint-ring located on the other side of said packing-rings comprising a pair of substantially semicircular members having flat end faces, one of said members being provided with recesses in its 80 peripheral surface and having apertures extending from said end faces to said recesses, clamping-screws operating in said recesses and engaging the ends of the other said member, a gland-plate engaging said joint-ring, 85 and means for securing said gland-plate to said stuffing-box.

In testimony whereof I affix my signature in presence of two witnesses.
